UNITED STATES PATENT OFFICE.

FORD W. HARRIS, OF LOS ANGELES, CALIFORNIA, ASSIGNOR TO MAGNETIC SIGNAL CO., OF LOS ANGELES, CALIFORNIA, A CORPORATION OF CALIFORNIA.

RAIL SPREADER.

Application filed February 23, 1926. Serial No. 89,911.

My invention relates to rail spreaders such as used for the purpose of spreading rails so that insulation may be inserted therebetween.

It is common practice to insulate a portion of railroad track from the other portion thereof, which insulated portion of track is used as a part of an electrical circuit for signaling devices. When a train runs over this portion of the track, the wheels thereof will electrically connect the insulated portion of track to the opposite portion of track in a manner to ground it and complete the circuit, thus operating the signal. Such insulation of a portion of track is accomplished by insulating the fish-plates from the rail and also by inserting insulation blocks between the ends of the rail which is to be insulated from the other portions of the track. For inserting these insulation blocks between the ends of adjacent rails a rail spreader is employed.

The ordinary form of rail spreader consists of a pair of threaded blocks which are secured to adjacent rail members and a turn-buckle screw by means of which the blocks may be spread in order to spread the rails apart so that a space will be created between the ends of the rails into which the insulation blocks may be placed. Rails of a track are secured together by fish-plates which are placed on each side of adjacent tracks at the joint and are secured thereto by bolts. The spacings of the holes through which the bolts for securing the fish-plates to the rails are not uniform, and it is ordinarily necessary to have different rail spreaders which are each proportioned to fit a different spacing of holes.

It is an object of my invention to provide a rail spreader which may be used on rails having different spacings of fish-plate bolt holes.

It is another object of my invention to provide a rail spreader having a novel form of adapter plate, by reason of which the rail spreader may be used on rails having different spacings of fish-plate bolt holes.

Other objects and particular advantages of this invention will be made evident hereinafter.

Referring to the drawings in which I illustrate a preferred form of my invention,

Fig. 1 is a perspective view of the rail spreader of my invention as applied to the

abutting ends of a pair of adjacent railroad rails.

Fig. 2 is a perspective view showing the manner of operating the rail spreader when applied as shown in Fig. 1.

Fig. 3 is a longitudinal section of the rail spreader of my invention secured to a pair of rails.

Fig. 4 is a fragmentary section taken on the line 4-4 of Fig. 3.

Fig. 5 is a fragmentary section taken on the lines 5-5 of Figs. 3 and 4.

The form of my invention shown in the drawings has a pair of blocks 11. The blocks 11 have nut portions through which longitudinal openings 12 are formed. The portions 14 of the longitudinal openings 12 are threaded. A turn-buckle screw 16 is provided with shaft portions 17 which extend through the openings 12 and which are threaded at 18 so as to screw into the threaded portions 14 of the openings 12. The central part of the turn-buckle screw 16 is provided with an enlarged cylindrical head 20 having openings 21 formed therethrough which are adapted to receive a bar whereby the turn-buckle screw 16 may be rotated. The threads 14 and 18 of the blocks 11 and shafts 17 are opposite in direction so that when the turn-buckle screw 16 is rotated in one direction, the blocks 11 are spread; and when the turn-buckle screw 16 is rotated in the opposite direction the blocks 11 are contracted.

The blocks 11 are provided with cavities 22 which separate the smooth portions and the threaded portions of the openings 12. At the bottom of the cavities 22 are longitudinally elongated openings 23. Extending from adjacent sides of the blocks 11 are flanges 24 in which longitudinally elongated openings 24^a are formed. The longitudinal axes of the elongated openings 23 and 24^a lie in the same horizontal plane and are of substantially the same length. Engaging each of the blocks 11 is an adapter plate 25. The adapter plates 25 have web portions 26 which are adapted to engage plane faces 27 of the blocks 11. Lugs 28 project outwardly from the opposite ends of the adapter plates 25 and provide shoulders 29 which engage outer end faces 30 and inner end faces 31 of the blocks 11.

The rail spreader of the invention is shown as secured to adjacent rails 32. The

rails 32 have vertical webs 34 which are provided with fish-plate bolt openings 35. The blocks 11 are secured to the rails 32 by means of bolts 36 which extend through the 5 fish-plate bolt openings 35. The bolts 36 have heads 37 which engage outer faces 38 which surround the longitudinally elongated openings 21 and 23 of the blocks 11. Adjacent to the heads 37 of the bolts 36 there 10 are provided elliptical portions 39 which rest in the longitudinally elongated openings 23 and 24^a and are for the purpose of keeping the bolts 36 from rotating. The adapter plates 26 have openings 41 formed 15 therein through which the bolts 36 extend and which are spaced the same distance apart as the fish-plate bolt openings 35 formed in the rails 32. The bolts 35 extend through back plates 42 which engage the 20 webs 34 on the sides opposite from the adapter plates 25, and nuts 43 are screwed onto the bolts for clamping the blocks 11 and the adapter plates 25 in place.

The operation of the invention is substantially as follows:

After the adapter plates 25 and the blocks 11 have been secured in place, as shown in the drawings, the blocks 11 are forced apart by rotating the turn-buckle screw 16 in the 30 proper direction by extending a bar 48 through one of the openings 21 and using this bar as a crank, as shown in Fig. 2. The thrust resulting from the spreading of the blocks 11 by the turn-buckle screw 16 is 35 transferred to the adapter plates 25 through the outer end faces 30 of the blocks 11 and the outer shoulders 28 of the adapter plates 25. There is no thrust transferred from the blocks 11 to the adapter plates 25 by means 40 of the bolts 36. The thrust is transferred from the adapter plates 25 to the rails 32 by means of the bolts 36.

In the manner described the adjacent rails 32 are spread apart so that a space is 45 made between the ends thereof and so that an insulation block 49, as shown in Fig. 1, may be inserted therebetween. A very important part of the invention resides in the 50 fact that the rail spreader of this invention may be used on rails having different spacings of fish-plate bolt holes. In using the rail spreader shown in the drawings on rails having fish-plate bolt holes 35 which are spaced farther apart, it is only necessary to 55 utilize a different pair of adapter plates which have openings therein which correspond to the spacing of the openings 35 in the rails 32. The bolts 36, since they extend into elongated openings 23 and 24^a in the blocks 11, may be adjusted to the desired 60 spacing. In Fig. 3 dotted lines 50 illustrate one of the bolts 35 as it may be placed when the openings in the rails are a greater distance apart than those shown by full lines. 65 The adapter plates 25 in this instance must

be provided with openings which align with the openings in the rails.

It will be seen that in my invention the same blocks 11 and turn-buckle screw 16 may be utilized on all rails regardless of the 70 spacing of the fish-plate bolt openings and that it is only necessary to have adapter plates with openings which correspond to the fish-plate bolt openings in the rails. A rail spreader outfit of my invention may 75 therefore consist of the blocks 11 and the turn-buckle screw 16 and a number of different pairs of adapter plates 25 which will attach the blocks 11 and turn-buckle screw 16 to any of the pairs of rails which are 80 to be spread. The bolts 36 will not fall from place when the nuts 43 are removed, since the shaft portion 17 of the turn-buckle screw 16 extends adjacent to the heads thereof which prevents the bolt heads from moving outwardly any great distance. 85

I claim as my invention:

1. A rail spreader comprising: a pair of blocks having longitudinally elongated openings; bolts adapted to extend through said 90 longitudinally elongated openings for attaching said blocks to adjacent rails, said bolts being adjustable in said longitudinally elongated openings so that said bolts may be aligned with openings in said rails; means 95 for forcing said blocks apart; and adapter members placed between said blocks and said rails through which thrust is transferred from said blocks to said rails.

2. A rail spreader comprising: a pair of blocks having longitudinally elongated openings; bolts adapted to extend through said 100 longitudinally elongated openings for attaching said blocks to adjacent rails, said bolts being adjustable in said longitudinally 105 elongated openings so that said bolts may be aligned with openings in said rails; means for forcing said blocks apart; and adapter members placed between said blocks and said rails through which thrust is transferred from said blocks to said rails, said adapter members having openings formed 110 therein through which said bolts extend, being of the same spacing as said openings in said rails. 115

3. A rail spreader comprising: a pair of blocks having longitudinally elongated openings; bolts adapted to extend through said 120 longitudinally elongated openings for attaching said blocks to adjacent rails, said bolts being adjustable in said longitudinally elongated openings so that said bolts may be aligned with openings in said rails; a turn-buckle screw threadably engaging said 125 blocks for forcing said blocks apart; and adapter members placed between said blocks and said rails through which thrust is transferred from said blocks to said rails.

4. A rail spreader comprising: a pair of blocks having longitudinally elongated open- 130

- ings; bolts adapted to extend through said longitudinally elongated openings for attaching said blocks to adjacent rails, said bolts being adjustable in said longitudinally elongated openings so that said bolts may be aligned with openings in said rails; means for forcing said blocks apart; and adapter plates engaging said blocks and being non-movable relatively thereto in a longitudinal direction, said adapter plates having openings therein which are the same spacing as said openings in said rails, said bolts extending through said openings in said adapter plates.
- 15 5. A rail spreader comprising: a pair of blocks having longitudinally elongated openings; bolts adapted to extend through said longitudinally elongated openings for attaching said blocks to adjacent rails, said bolts being adjustable in said longitudinally elongated openings so that said bolts may be aligned with openings in said rails; a turn-buckle screw threadably engaging said blocks for forcing said blocks apart; and adapter
- 20 plates engaging said blocks and being non-movable relatively thereto in a longitudinal direction, said adapter plates having openings therein which are the same spacing as said openings in said rails, said bolts ex-
- tending through said openings in said adapter plates.
6. A combination as specified in claim 4 in which said adapter plates have end shoulders engaging said blocks for effecting said relative longitudinal non-movability.
7. A rail spreader comprising: a pair of blocks; bolts for attaching said blocks to adjacent rails; means for forcing said blocks apart; and adapter members placed between said blocks and said rails through which thrust is transferred from said blocks to said rails.
8. A rail spreader comprising: a pair of blocks having longitudinally elongated openings; bolts adapted to extend through said longitudinally elongated openings for attaching said blocks to adjacent rails, said bolts being adjustable in said longitudinally elongated openings so that said bolts may be aligned with openings in said rails; means for forcing said blocks apart; and adapted members through which thrust is transferred from said blocks to said rails.

In testimony whereof, I have hereunto set my hand at Los Angeles, California, this 15th day of February, 1926.

FORD W. HARRIS.
